(57) **ABSTRACT**

Extended adapters for a tool having a shut-off valve assembly used on pressurized refrigeration systems comprises: an extended rod assembly, a 4 1/8" L adapter, a 6 7/8" L adapter, a 20 degree offset adapter and a 90 degree adapter; the adapters couple the first opening and second opening of shut-off valve assembly; when the 4 1/8" L or 6 7/8" L extended adapter coupled to second opening of shut-off valve; wherein the extended rod assembly coupled to the adapter and adapted to couple the second opening, the extended rod assembly having a rod adapted to move through the passageway of the extended adapters and the shut-off valve when open, these adapters allow the valve core remover tool to function clear from obstructions.

VALVE CORE REMOVER EXTENSION

BACKGROUND OF INVENTION

In the HVAC field it has become very important, when servicing pressurized refrigeration systems, to remove and replace leaking valve core elements. The EPA has a great concern on the handling and release of refrigerant gases. There is a tool on the market used in the HVAC field that will safely remove and replace valve core elements, such as the Schrader-type from pressurized air conditioning systems. This tool is called a valve core removal tool, comprising a shut off valve assembly, but there is issues with this tool being obstructed, and is unable to couple onto many air conditioning systems valve access points.

There seemed to be a need for a solution, so the valve core extensions were created in several variations to assist and provide the existing valve core remover tool better accessibility from obstructions.

SUMMARY OF THE INVENTION

The present invention is a set of extended adapters that is capable of being used with a tool for pressurized refrigeration systems. The adapter set comprises: a 4 1/8" L adapter, a 6 7/8" L adapter, a 20 degree offset adapter, a 90 degree adapter and an extended rod assembly, and are able to couple to the tool used for pressurized refrigeration systems shut-off valve assembly, allowing the same passageways needed to engage and remove the valve core elements.

FIELD OF THE INVENTION

This invention is capable of being used with a tool for removing valve elements from pressurized air conditioning systems.

BRIEF DESCRIPTION OF THE DRAWINGS

FIGS. 1 and 1a show the various components of the extended rod assembly 500.

FIG. 2 illustrates preparing of the universal line service valve.

FIG. 3 illustrates preparing of the compression nut.

FIG. 4 shows preparation and assembly of the 4 1/8" L straight extension adapter 600.

FIG. 5 shows preparation and assembly of the 6 7/8" L straight extension adapter 700.

FIG. 6 shows preparation and assembly of the 2 1/2" L offset extension adapter 800.

FIG. 7 shows preparation and assembly of the ninety degree extension adapter 900.

FIG. 8 shows extended rod assembly and extension adapters assembled to the shut-off valve assembly.

DETAILED DESCRIPTION OF DRAWINGS
(FIGS. 1-8)

FIG. 1a depicts the materials for the extended rod assembly.

FIG. 1 prep & assemble; extended rod assembly 500, apply JB weld epoxy to one end of steel cable 3a, and insert extractor head 1a, to steel cable 3a, apply JB weld to small nail 2a, insert through small hole of extractor head 1a, and allow epoxy to setup. Apply JB weld 3/4" to opposite end of steel cable 3a, insert steel cable 3a, in to 3/4" x 1/8" deep hole

2

of rod 4a, apply JB weld to small nail head 5a, and imbed on to small hole, side of rod 4a, and allow epoxy to setup. Note: The bonding agent may vary from JB weld to soldering or brazing, etc.

Opposite side of rod 4a, insert compression nut 6a, sliding threaded end through first. Imbed rod control knob 7a, to rod 4a, insert 1/8" set pin 8a, through hole of rod control knob 7a, and rod 4a.

FIG. 2 debraze and separate service valve 101 from 10 copper tube discarding copper tube. Bore through service valve 101 with 1/4" drill bit. Four service valves needed for this kit.

FIG. 3 compression nut 102 is removed from a hvac 15 refrigerant hose. Bore through compression nut 102 with 5/16" drill bit carefully not damaging inner threads. Four compression nuts are needed for this kit.

FIG. 4 prep & assemble; 4 1/8" L straight extension adapter 600. 5/16" D x 3 1/8" L copper tube 103, swedge one end of copper tube 103 to 3/8", and insert compression nut 102 20 sliding threaded end through first. Swedge opposite end of copper tube 103 to 3/8" insert and braze service valve 101 to this end of copper tube 103.

FIG. 5 prep & assemble; 6 7/8" L straight extension adapter 700. 5/16" D x 6 7/8" L copper tube 104; swedge one end of copper tube 104 to 3/8", and insert compression nut 102 25 sliding threaded end through first. Swedge opposite end of copper tube 104 to 3/8" insert and braze service valve 101 to this end of copper tube 104.

FIG. 6 prep & assemble; 2 1/2" L offset extension adapter 800. 5/16" D x 2 1/2" L copper tube 105, bend copper tube 105 twenty degrees and swedge one end to 3/8", and insert compression nut 102 sliding threaded end through first. 30 Swedge opposite end of copper tube 105 to 3/8" insert and braze service valve 101 to this end of copper tube 105.

FIG. 7 prep & assemble; ninety degree extension adapter 900. 5/16" D x 6 1/8" L copper tube 106; bend copper tube 106 ninety degrees and swedge one end to 3/8", and insert 35 compression nut 102 sliding threaded end through first. Swedge opposite end of copper tube 106 to 3/8" insert and braze service valve 101 to this end of copper tube 106.

FIG. 8 Extended rod assembly 500, straight extension adapter 600, and 2 1/2" L offset extension adapter 800 40 assembled to the shut-off valve assembly of said tool for pressurized refrigeration systems.

What I claim:

1. A set of adapters and an extended rod assembly that works with an existing tool for pressurized refrigeration systems having removable valve core elements, comprising: an extended rod assembly, a 4 1/8" long adapter, a 6 7/8" long adapter, a 20 degree offset adapter and a 90 degree adapter; said existing tool having a first opening and a second opening and a shut-off valve, said shut-off valve having 50 positions to open and close a passageway between said first opening and said second opening; said 4 1/8" long adapter threads to said second opening, extending said passageway of said shut-off valve; said extended rod assembly threads to said 4 1/8" long adapter; said 20 degree offset adapter, said 55 6 7/8" long adapter, and said 90 degree adapter threads to said first opening extending said passageway of said shut-off valve; said extended rod assembly having a rod to move through passageways of said adapters, when said shut-off valve is open, and engage with the said adapters to the 60 pressurized refrigeration systems having said removable valve core elements, and said extended rod assembly further having a threaded portion controlling axial movement of

said rod through said passageways of said adapters and said shut-off valve; wherein to provide said existing tool clearance from obstructions and the said removable valve core elements can be removed and replaced, while under pressure. 5

2. The adapter set as recited in claim 1 wherein said 4 1/8" long adapter comprises threaded fittings.

3. The adapter set as recited in claim 1 wherein said 6 7/8" long adapter comprises threaded fittings.

4. The adapter set as recited in claim 1 wherein said 20 10 degree adapter comprises threaded fittings.

5. The adapter set as recited in claim 1 wherein said 90 degree adapter comprises threaded fittings.

6. The extended rod assembly as recited in claim 1 wherein said extended rod assembly is configured to thread 15 to said 4 1/8" long adapter threaded to said second opening of said shut-off valve.

7. The set of adapters as recited in claim 1 wherein said 6 7/8" long adapter, said 20 degree adapter, and said 90 degree adapter are configured to thread to said first opening of said 20 shut-off valve.

8. The set of adapters and the extended rod assembly as recited in claim 1; wherein to provide said existing tool clearance from obstructions said removable valve core elements can be removed and replaced, while under pressure. 25
